INVENTION.

Anthony Bartolomaei
La Porte & La Porte
ATTY'S

UNITED STATES PATENT OFFICE.

ANTHONY BARTOLOMUCCI, OF PEORIA HEIGHTS, ILLINOIS.

DISPLAY SIGN.

Application filed August 12, 1926. Serial No. 128,787.

This invention has reference to display signs of that type including a series or a plurality of rotatable members having changeable display surfaces and actuating means for presenting such surfaces to display in gradual succession and at intervals momentarily holding such display surfaces at a period of rest.

The principal object of the present invention is to provide a series or a plurality of rotatable members each preferably rectangular in cross section whereby to provide each member with preferably four flat display surfaces and thereby increase the surface area in signs of this character for advertising purposes, thus increasing the display surfaces of such signs.

A further object of the invention is to provide a novel means for rotating the display members, of the character herein referred to, so that when the members have their surfaces in display position, they are in superimposed relation next adjacent to each other so as to present a substantially continuous or unitary surface area throughout to facilitate a display sign the characters or figures of which may have an overlapping or continuous relation, one onto the other, of each of the adjacent surfaces of said display members.

To the accomplishment of the foregoing objects, the members are so journaled in the supporting frame and the means for rotating the same is so arranged that certain of the members have imparted thereto during their rotative movement, a vertical movement whereby to space such members in relation to each other to permit them to be turned on their axes so as to present their successive display surfaces in display relation to each other; the rotation of the alternate members being in preferably a reverse direction.

In the preferred arrangement of the display members, they rotate on horizontal axes, one of which preferably rotates in a fixed horizontal plane, whereas the remaining members rotate on horizontal axes which are changeable during the rotation of the members and when the display surfaces of such members are in display position, such members assume their initial axial position with the members in approximate juxtaposition so as to present a display surface sub-

stantially continuous throughout the several members.

That the invention may be more fully understood, reference is had to the accompanying drawings forming a part of the present description and illustrating a preferred embodiment of the invention, in which:

Figure 1 is a front elevation, partly in cross-section showing a display sign embodying my invention, the display members having certain of their respective display surfaces in normal display position, and with an outline for a casing therefor shown in dotted lines;

Figure 2 is an elevation of the sign looking in at the right hand end of Figure 1;

Figure 3 is a fragmentary elevation, partly in cross section of the parts shown in Figure 1, except that the display members and the actuating means therefor are in the position they assume as the members are being rotated;

Figure 4 is an end elevation looking in at the right hand end of Figure 3, and

Figure 5 is a cross section of the display members as they appear in Figure 3.

Like characters of reference denote corresponding parts throughout the figures.

Referring to the drawings, the frame of the sign preferably comprises the spaced end standards or supports 1 secured in this relation at their upper ends by means of the connecting bar 2 and at or near their lower ends by the preferably driving shaft 3, supplemented by shafts 4, 5 and 6 which carry the respective display members 7, 8 and 9. These members are shown in preferably horizontal position between the standards or supports 1 and in a superimposed relation to each other. The standards or supports 1 may have rest members 10 and the supporting means, the display members and actuating means therefor may be enclosed in a suitable housing 11 shown in outline in dotted lines and such housing would have a display opening 12 which may be transparent or otherwise which surrounds the immediate area in which the display members would be exposed when in sign display position.

The shaft 4 carrying the member 7 is journaled in the supports so as to rotate in a substantially fixed horizontal plane. The shaft 5 which carries the member 8 is preferably journaled in slots 13 having a vertical

disposition as the standards or supports 1 and the shaft 6 carrying the member 9 is likewise journaled in similar slots 14 in the standards or supports 1. These latter slots 5 are of greater depth than the slots 13 and said shafts 5 and 6 when they are rotated have simultaneously imparted thereto a vertical movement, which movement changes the horizontal axial position for the purpose of separating and raising the members 8 and 9 in relation to each other and the member 8 in relation to the member 7 so as to permit the members 8 and 9 to be rotated in relation to each other and the member 8 in relation to the member 7, each of which is rotated in unison with the other. As shown, the members 7, 8 and 9 are preferably rectangular in cross-section, thereby providing each with four display surfaces and such members when in display position are in superimposed relation, in approximate juxtaposition, presenting a substantially continuous unitary surface throughout which facilitates variable display signs, the characters or figures of which may appear to be continuous by overlapping on the respective display surfaces of adjacent members, when their surfaces are in display position. With such a construction and in the provision of an enlarged display surface in members of this character, wherein the changeable surface area is increased, which is made possible by constructing the members of rectangular formation, their successive display surfaces can only be brought into display position by journaling these members in a manner which will permit certain of them to be raised, whereby to separate them when they are being turned with relation to each other to present successively new display surfaces. In other words, these members must be journaled in a manner so that when they are rotated they must be free and unobstructed due to the peculiar character of the members, which as stated, are rectangular in cross-section and when in display position have the appearance of resting one upon the other.

The gearing which I have adopted for rotating the members 7, 8 and 9 is duplicated at the opposite ends of the sign and is of such a character as will impart rotative movement to each of the shafts 4, 5 and 6 from the driving shaft 3 and it is during such movement that the shafts 5 and 6 are raised in their bearings whereby to separate the members 8 and 9 from each other and the member 8 from the member 7 which will permit the members 8 and 9 to be rotated in unison with the member 7, and such gearing is also of such a character that momentarily and at certain periods, being the periods when corresponding surface portions of the members are in display position, the members are at rest, and after such momentary

stoppage rotative movement is continued so as at successive intervals changeable display surfaces on the members are successively presented. Furthermore, the gearing which I have adopted is somewhat of the Geneva 70 wheel type, the respective inter-related elements comprising pin and slotted wheels having coacting cam surfaces. While this form of gearing is practical for the purposes herein intended, it will appear obvious 75 that other forms of gearing may be substituted. For purposes of expedition and simplicity, I shall describe the gearing for corresponding ends at one end of the shafts 4, 5 and 6 and it will be understood that such 80 gearing is duplicated for the respective shafts at the other end of the sign. In this way provision is made for driving and rotating the respective members at opposite ends and also for applying a lifting movement to 85 the opposite ends of the shafts 8 and 9. To the driving shaft 3 is connected a disc wheel 15 having preferably two pins 16 disposed diametrically opposite each other and such disc is provided with duplicate cam surfaces 90 17. To the shaft 4 is connected a disc 18 with preferably four radial slots 19 extending inwardly from the surface of the disc and diametrically disposed with relation to each other and the surface of this disc between said slots is dished at 20 with which at intervals coincide and ride on the cam surfaces 17 of the disc 15. As the latter rotates, its pins 16 successively enter the slots 19 of the disc 18 to rotate such disc and the shaft 4; the slots 19 being of sufficient depth that the pins 16 may have a reciprocal movement therein, while at the same time the disc 18 is rotated. It is when the cam surfaces 17 of the disc 15 are coincident with the dished surfaces 20 of the disc 18 that the display members are at momentary rest in display position and such coaction of these elements, as will be understood, prevents accidental dislodgment of the respective display members, which may be caused by wind pressure or otherwise. To the shaft 4 and in front of the disc 18 is connected a disc 21 which is provided with pins 22 of which there are preferably four arranged diametrically in relation to each other and to the disc 21 is connected a smaller annular plate 23. The pins 22 of the disc 21 are adapted to enter seats 24 in the periphery of a disc 25 connected to the shaft 5. This disc is somewhat similar to the disc 18 having preferably four seats 24 and interposed dished portions 26 corresponding to the dished portions 20 of said disc 18, and the periphery of the annular plate 23 rides in the dished portions 26 as they are successively presented thereto. To the shaft 5 in front of the disc 25 is connected a disc 27 similar to the disc 21 in that it is provided with pins 28, preferably four, diametrically disposed in rela- 110 115 120 125 130

tion to each other and on the disc 27 is an annular plate 29 similar to the plate 23 on the disc 21. These pins 28 are adapted to have a coacting relation with seats 30, of which there are preferably four, arranged in the periphery of a disc 31 connected to a shaft 3 and in the periphery of said disc between said seats 30 are provided dished surfaces 32. In all respects the disc 31 is similar to the disc 25 on the shaft 5.

In operation the driving shaft 3 is continuously operated from any suitable source of power, not shown, and as this shaft is rotated movement is imparted to the disc 15 and as its pins 16 enter the slots 19 of the disc 18, rotative movement is imparted to the shaft 4 which in turn imparts rotative movement to the disc 21 and it, through its pins 22 entering the seats 24 in the disc 25 imparts rotative movement therethrough to the shaft 5, which in turn imparts rotative movement to the disc 27 connected thereto, which, through its pins 28 entering the seats 30 of the disc 31 imparts rotative movement to the shaft 6. The annular plates 23 and 29 on the respective plates 21 and 27 coacting with the dished portions 20 and 26 of the respective discs 25 and 31 function as do the cam surfaces 17 and the dished portions 20 of the respective discs 15 and 18 to momentarily hold their respective display members at rest and against accidental dislodgment.

From the form and arrangement of the gearing, as shown, it will be apparent that the radial slots 19 in the disc 18 permits the pins 16 on the disc 15 to enter and leave the same and accomplish the rotation of the shaft 4 without the displacement of its axis, but that the arrangement of the shallow recesses in the disc 25 and in the disc 31 when the respective pins 22 and 28 coact therewith to impart rotative movement to the respective shafts 5 and 6 necessarily lifts the latter to accomplish the separation of the members 8 and 9 from each other and the member 8 from the member 7 to permit their being rotated in relation to each other. The slots 13 and 14 in the standards or supports 1 allow for the vertical movement of the respective shafts 5 and 6 as they are rotated.

What I claim is:

1. In a sign, a rotatable sign carrier, means to rotate the carrier, a bodily shiftable and rotatable sign carrier disposed adjacent to the first carrier, means carried by the first carrier and operable thereby to bodily shift and rotate the second carrier in one direction, and means on the second carrier cooperating with the means on the first carrier whereby shifting and rotation of the second carrier is effected.

2. In a sign, a plurality of alined rotatable contacting display members, one of said members having a substantially fixed axis and the other members having axes adapted

to be shifted relative to the first mentioned member and to each other, means carried by the members for effecting rotation of the members in one direction, rotatable cooperating means carried by the members for effecting lateral separation of the members to permit rotation of the members in unison, and means to effect a momentary pause of the members when corresponding surfaces are in display position.

3. In a sign, a plurality of alined rotatable contacting display members, one of said members having a substantially fixed axis, the other of said members having axes adapted to be shifted relative to the first mentioned member, means carried by the members for effecting rotation of the members in one direction, means carried by each of the members for effecting lateral separation of the shiftable members to permit rotation in unison, and means to effect a momentary pause of all the members when corresponding surfaces are in display position whereby to present a continuous stationary display area.

4. In a sign, a rotatable sign carrier, means to rotate the carrier, a bodily shiftable and rotatable sign carrier disposed adjacent to the first carrier, cam means carried by the first carrier and operable thereby to bodily shift and rotate the second mentioned carrier in one direction, and means on the second mentioned carrier cooperating with said cam means on the first carrier whereby shifting and rotation of the second carrier is effected.

5. In a sign, a rotatable sign carrier, means to rotate the carrier, a bodily shiftable and rotatable sign carrier disposed adjacent to the first carrier, cam means carried by the first carrier, cam means carried by the second carrier and cooperating with the cam means of the first carrier to effect bodily shifting of the second carrier, and means carried by the first carrier cooperating with the means on the second carrier to effect rotation of the second carrier.

6. In a sign, a rotatable sign carrier, means to rotate the carrier, a bodily shiftable and rotatable sign carrier disposed adjacent to the first carrier, a cam plate carried by the first carrier, a cam plate carried by the second carrier, studs carried by the cam plate on the first carrier adapted to engage the cam plate on the second carrier to effect bodily shifting of the second carrier, and means carried by the first carrier cooperating with the means on the second carrier to effect rotation of the second carrier.

7. In a sign, a rotatable sign carrier, means to rotate the carrier, a bodily shiftable and rotatable sign carrier disposed adjacent to the first carrier, a plate carried by the first carrier having a uniform periphery, a plate carried by the second carrier having

diametrically opposed concavities, axially projecting studs carried by the face of the plate on the first carrier adjacent its periphery to engage the periphery of the plate carried by the second carrier to effect bodily shifting thereof, the periphery of the first plate being formed to engage in the concavities of the second plate to permit a momen-

tary pause of the carriers when corresponding surfaces are in display position whereby to present a continuous stationary display area, and means to rotate the first carrier.

In witness whereof, I have hereunto affixed my hand and seal this 6 day of August, 1926.

ANTHONY BARTOLOMUCCI.
